UNITED STATES PATENT OFFICE

WALTER F. HAMMEL, OF CHICAGO, ILLINOIS, ASSIGNOR TO ESTHER S. HAMMEL, OF CHICAGO, ILLINOIS

ENVELOPE

Application filed July 16, 1919. Serial No. 311,280.

My present invention relates in general to envelopes, and more particularly to envelopes of the type known as "penny-savers" wherein there is a portion which may be 5 opened by the postal authorities for the inspection of the contents thereof, or for the removal of such contents for such inspection, and has special reference to improvements in envelopes of the character referred to in 10 which the so-called loose portion or flap is normally engaged and held from opening out by another portion of the structure or by the relative disposition of the parts.

The principal objects of my present invention are the provision in an envelope of the type referred to of improved means whereby the loose flap is normally retained in predetermined closed position by means of the back of the envelope—more particularly means carried by the back of the envelope; the provision of a cooperative hook and pocket formed on said flap and back respectively in aid of such purpose; the provision of an envelope of the class referred to characterized by the attachment to the inner surface of the 25 back of the structure of a pocket arranged for engagement by the loose flap folded reflexively from the edge portion of the envelope whereby the finished structure is greatly 30 strengthened, and danger of accidental disengagement of the loose flap from such back largely prevented, together with such other objects as may be hereinafter disclosed.

In gaining the foregoing objects and certain 35 additional benefits and advantages, which will herein below appear, I have provided a structure, certain embodiments of which are illustrated in the accompanying drawings, wherein—

Figure 1 is a diagrammatic view of blank 40 from which is made an envelope embodying one form of my present invention, the creases formed in folding the blank in the course of the manufacture of the article being indicated by dotted lines;

Figure 2 is a similar view exhibiting one of 45 the steps of manufacture, including the folding of the flaps, but showing a modified form of structure;

Figures 3 and 4 are similar views showing

the consecutive steps of folding in such manufacture; and

Figures 5 and 6 are respectively a back view of the completed article, and a sectional view thereof with an inclosure therein.

Referring first to Figure 1 of the drawings, it will be noted that the envelope herein illustrated is distinctly of the "high-back" type, and comprises the customary portions, viz.: a front, A, a back, B, side or end flaps, 60 C—D, and a top or sealing flap, E.

In carrying out my invention I have provided on the back, B, a supplemental portion, F, which I will term the "auxiliary strip" and where desirable I employ in connection 65 therewith one or more portions G, G, which, when the envelope is in practical use, act in effect as elongated slotted apertures adapted for the reception of upward projections H, H, preferably hook shaped, formed on the 70 flaps, C, D.

In the manufacture of the envelope, folds are consecutively made on the lines j, k and m in the customary manner, such steps being illustrated in Figures 2 and 3 respectively, 75 whereupon the projections, H, H are embraced between the back, B, and auxiliary strip F adjacent the openings G, G (see Figure 3), since the strip F being spotted by adhesive as indicated at p, p' becomes attached to the back, such strip F having been first placed in position as indicated in Figures 1 and 2, thus producing the arrangements shown in Figures 3 and 4.

On examination of Figure 4 it will be apparent that the end flaps C, D are substantially covered by the back B, and that the loose end flaps are embraced closely between it and the auxiliary strip F which holds them securely in position. As it is of importance 85 that the flaps C and D be left unconnected together, they are preferably of less total length than the length of the back B.

The sealing flap E is shown as provided with the customary adhesive portion, which 95 may be provided thereon throughout the usual full portion of its length as indicated by the stippling z and sealed down against the back B, without danger of unintentionally securing the end flaps C, D, against 100

opening, in view of the extreme width of the back B and the manner in which it covers the end flaps C, D.

Ordinarily, I prefer to omit the projection 5 H on one of the flaps, such as the flap D, and likewise the corresponding pocket G, and in such cases preferably cause such flap to adhere to the back B by means of an adhesive applied to a portion of the flap, as indicated 10 by the stippling at α , such flap D then becoming a "closed flap" but the flap C remains an "open flap."

Those skilled in the art to which my invention pertains will appreciate that while the 15 cooperating hooks and openings H—H, G—G, are highly advantageous, for certain purposes one or both may be omitted, that the adhesive α may be applied indifferently to the flap C or to the flap D, or to an opposite 20 portion of the back, and that aside from the "penny-saver" features of my improved envelope which afford a maximum of strength, the most desirable appearance, and the minimum of difficulties in manufacture, 25 articles may be inserted into such envelope with the greatest of facility and despatch and with a minimum of loss of time either from accidental derangement of the folds or from catching or other interference by such 30 folds or with such insertions or inclosures.

I have heretofore proposed to form an envelope having a front portion A provided with a flap E and a back portion B provided with a flap F, and likewise C and D, such 35 flap F being formed integrally with the back B and provided with slots adapted to receive hooks on the flaps C and D, as shown in Letters Patent No. 1,230,154 of June 19, 1917, and consequently the structure referred to is 40 not intended to be included within the scope of my claim.

Those skilled in the art will further appreciate the facts that by utilizing an auxiliary strip F and fastening it securely against 45 the back B, as by means of gum or other adhesive spotted indifferently at the places indicated by p and p' on the strip F, or at corresponding places on the back B, a number of marked advantages are attained. 50 Some of these are technical, and others are commercial.

Among the technical or structural advantages are these, that owing to the fact that the strip F is fixedly held in position it is 55 not only much more readily produced in quantity by machinery, but the resultant structure is stronger and also more compact; that it being rendered possible to use quite a large hook H, there is less likelihood 60 of accidental disengagement of the hook H from the aperture G or the pocket therebelow formed by the gum-spots p , p' , either in service or in inserting the contents into the envelope; that such a large hook is of advantage too in that it has proportionately

greater strength and is less apt to bend, break or tear, and thus to become misplaced, inefficient or impotent in service; and that the lower margin of the strip F being held down and against the back B any chance of 70 dislocation of the strip by the contents inserted into the envelope is removed.

Among the commercial advantages are the following: that the present form of envelope may be made on high-speed envelope 75 making machines having a capacity greater by from 30% to 50% than that of machines for making envelopes wherein the hook has to be inserted into a slot formed marginally 80 along the line of fold where it is connected to the back B; that there is a material saving in paper stock since a smaller size of paper sheet can be used, or, in the case of larger sheets a greater number of envelope blanks can be cut from the sheet; that the 85 marginal slot-punching operation is saved; that the cutting dies are simplified and that danger of "choking" thereof incident to punching small slots is obviated; that there is a decreased envelope wastage owing to 90 simplification of manufacture; that less expensive labor, dies, and machinery can be employed; and that making due allowance for the slight cost of the strip F and of gumming it in position, the resultant envelopes can be profitably sold at from one 95 third to one quarter less than those employing the inwardly folded flap and marginal slot.

Having thus described my invention and 100 illustrated its use, what I claim as new and desire to secure by Letters Patent is:

An envelope having a front and a back portion, the back including two end flaps lying against the front between the latter 105 and said back portion, one of said flaps being sealed and the other loose and having a hook-like portion projecting into the envelope adjacent to the open mouth thereof adapted to lie between the front and back 110 adjacent to one corner of the envelope so as not to interfere with the insertion of the contents of the envelope or materially increase the thickness thereof adjacent to the lock, and an auxiliary member secured to 115 the back adjacent to said hook-like portion and having an anchor to receive said hook-like portion in the closed position of the loose end flap, thereby leaving the mouth portion unobstructed throughout its entire 120 dimension.

In testimony whereof I have hereunto signed my name.

WALTER F. HAMMET.
